METHOD AND MEANS OF BURNING SOLID FUEL

Thomas McDonald and Clifford J. Paisley, Toronto, Ontario, Canada, assignors to Minneapolis-Honeywell Regulator Company, Minneapolis, Minn., a corporation of Delaware

Application April 6, 1932, Serial No. 603,550

18 Claims. (Cl. 236—9)

The present invention relates to improvements in the method and mechanism for burning solid fuel particularly under automatic control for domestic purposes.

- 5 In one of the well known types of prior art devices for automatically burning solid fuels it has been usual to supply fuel and air simultaneously and concurrently whenever the temperature of the space to be heated became less than 10 that desired. In such systems wherein the fuel and air feeds are simultaneously started and stopped, it often happens that large quantities of unburned fuel are discharged into the ash pit, resulting in a serious loss in economy in operation. 15 This is due to the fact that only slow and desultory burning of the fuel is present after the air feed is stopped. When the air and fuel feeding means are again started a large quantity of unburned fuel is likely to be left in the fire-box 20 which fuel in turn is displaced into the ash pit upon the feeding of fresh fuel.

In order to overcome this difficulty it has been proposed to operate the fuel feed for a given percentage of time that the air feed is operated. 25 In this manner it has been possible to prevent a certain amount of the discharge of unburned fuel from the fire-box into the ash pit but this system of burning solid fuel does not take into account the varying rates at which the same fuel 30 may burn under different conditions of operation. In an effort to overcome the condition where unburned fuel is disposed in the ash pit, it has been proposed to feed air constantly even when the space to be heated is above the desired 35 temperature but, of course, it will readily be appreciated that in such a system, while the discharge of unburned fuel might be prevented, on the other hand the fuel is, of course, being burned more rapidly than desired during such 40 times as the space to be heated is at or above the desired temperature.

The primary object of the present invention is to provide a method and mechanism for burning solid fuel preferably under automatic control 45 for domestic use in which the disposing of unburned fuel in the ash pit will be avoided so far as is practicable without burning the fuel at an unduly high rate during periods when the space to be heated is at or above the desired temperature.

50 It has been found that the temperature of combustion has a definite relation to the burning capacity of the furnace and that when the furnace has received all of the fuel that it can 55 adequately handle and completely burn the tem-

perature of combustion will rise to a point indicating that such a condition has been reached and that no more fuel should be fed to the furnace until the temperature of combustion becomes lowered.

An object of the present invention, therefore, is the provision of a mechanism which will normally feed fuel and air at the same time whenever the space to be heated falls below that temperature which it is desired to maintain and to discontinue the feeding of fuel but continue the feeding of air when the temperature of combustion rises to a point indicating that the furnace has been supplied with that amount of fuel which it can economically and completely burn.

More specifically, we provide two electric devices, one of which controls the feed of fuel and the other of which controls the feed of air to a furnace. These two electric devices are normally under the control of a thermostat usually referred to as the room thermostat so that they are operated whenever the room falls below the desired temperature. A second thermostat which is subject to the temperature of combustion interrupts operation of the electric device which controls the feed of fuel whenever the temperature of combustion rises above a point indicative of the condition wherein all of the fuel that can be handled by the furnace has been supplied to it. The combustion thermostat, however, does not discontinue feeding of air while the room thermostat is still below the desired temperature.

A further object of the invention is the provision of means for preventing extinguishment of the fire under low heat requirement conditions 35 in combination with the devices above mentioned.

Further objects of the invention will become apparent as the description thereof proceeds.

For a further and more complete understanding of the invention reference may be had to the following description and accompanying drawing, in which:

Figure 1 is a diagrammatic view showing one manner in which our invention may be carried out.

And Figure 2 is a sectional view with parts broken away of one type of combustion thermostat that may be utilized in the system of Figure 1.

Referring to the drawing, a thermostat adapted to be placed in the space to be heated and hereinafter referred to as the room thermostat is generally indicated at 10. The room thermostat comprises a bimetallic element 11 secured at

one of its ends as indicated at 12 and carrying a contact at its other end as indicated at 13. Contact 13 engages a cooperating contact 14 whenever the temperature to which the room 5 thermostat is subjected falls below a predetermined minimum.

A combustion thermostat generally indicated at 15 may comprise a casing 16 to which is secured a laterally extending tubular member 17. A helically coiled bimetallic element 18 has one of its ends secured to the outer end of tubular member 17. A torsion rod 19 which terminates within casing 16 extends through tubular member 17 and helical bimetallic coil 18 and has its outer end 10 bent to substantially a right angle in respect to the axis of the torsion rod as shown at 20. The free end of the part 20 of torsion rod 19 is secured to the outer free end of bimetallic element 18 by any suitable means such as the nuts 21. The end 15 of torsion rod 19 which extends into and terminates within casing 16 is provided with screw threads as shown at 22. Torsion rod 19 supports a pair of arms 23 and 24 which are adjustably secured thereto by means of pairs of nuts 25 and 26 which are received on the screw threaded portion 25 thereof. Each of the arms 23 and 24 is provided with a mercury switch holder 27 and 28 which in turn support mercury switches 29 and 30. The mercury switches 29 and 30 are 30 of usual construction and comprise sealed containers of suitable glass into which extend electrodes which cooperate with a body of mercury for making and breaking contact between the electrodes as the mercury switches are tipped or rocked. As hereinbefore stated, the arms 23 and 35 24 are adjustably mounted on torsion rod 19 and for use in this particular system the switch 29 will be known as a low limit switch and is adjusted so as to close a circuit whenever the combustion temperature falls below approximately 40 150° F. Likewise the switch 30 will hereinafter be referred to as a high limit switch and it is so adjusted that it opens a circuit whenever the temperature of combustion rises above a predetermined maximum temperature of about 500° F. 45

The combustion thermostat 15 may be placed in the stack of the furnace or at any other point wherein it responds directly and quickly to the temperature of the products of combustion or of 50 the fire itself. It may respond only to the temperature of the products of combustion or to radiant heat from the fire or to any combination of them so long as the temperature of the combustion thermostat quickly responds to the 55 changes of the condition of the fire and is subjected to a temperature which bears some direct relation to the condition of the fire.

The fuel feed means and the air feed means are herein shown as electric motors numbered 31 60 and 32 respectively which may operate the conventional screw feed and air blower. The system also includes a relay having a coil 33 which operates an armature 34 which in turn controls a contact arm 35 adapted to cooperate with a 65 stationary contact 36. The relay in this particular instance is of that type which moves contact arm 35 from engagement with contact 36 under the action of gravity when coil 33 is de-energized and in which the armature 34 positively moves 70 contact arm 35 into engagement with contact 36 when relay coil 33 is energized.

Operation

With the parts in the position shown the room 75 or space to be heated is above the desired tem-

perature and the temperature of combustion is above the minimum for which low limit switch 29 is set and below the maximum for which high limit switch 30 is set. The fuel and air feed motors 31 and 32 are not being operated and consequently the temperature of the room is lowering. When the temperature of the room has lowered sufficiently, bimetallic element 11 will cause contact 13 to engage contact 14 setting up the following energizing circuit for relay coil 10 33; hot line 37, wires 38, 39, bimetallic element 11, contact 13, contact 14, wire 40, relay coil 33, and wire 41 to ground line 42. Energization of relay coil 33 attracts armature 34 to move contact arm 15 35 into engagement with contact 36. Such action energizes feed motor 31 as follows: hot line 37, wire 43, contact 36, contact arm 35, wire 44, wire 45, high limit switch 30, wire 46, feed motor 31, wire 47, and wire 48 to ground line 42. Fan motor 32 is simultaneously energized by the following circuit: hot line 37, wire 43, contact 36, contact arm 35, wire 44, wire 49, fan motor 32, wire 50, and wire 48 to ground line 42.

The temperature of combustion begins to rise as a result of operation of the fuel and air feed 25 and when the temperature of combustion rises above the setting of high limit switch 30 the circuit to the fuel feed motor 31 will be interrupted. Such action indicates that the furnace 30 has been supplied with as much fuel as it can completely burn. It will be noted that the supply of air is not interrupted since the circuit of fan motor 32 is not controlled by the high limit switch 30.

Heat is still generated by the furnace since it 35 has been provided with its full capacity of fuel and air under forced draft is still being supplied. Should the fuel which has been supplied to the furnace become consumed to such an extent that the temperature of combustion again lowers, high 40 limit switch 30 will re-establish a circuit through feed motor 31 and more fuel will be fed until the combustion temperature again rises above the setting of the high limit switch 30 indicating that the condition wherein the furnace has been 45 supplied with all the fuel it can completely burn has again been reached. This intermittent operation of the fuel feed motor 31 in accordance with the temperature of combustion will continue until the room has been restored to the temperature 50 it is desired to maintain whereupon bimetallic element 11 will separate contact 13 from contact 14 completely shutting down the system.

In this system provision is also made for operating the fuel and air feed sufficiently often 55 to prevent a complete consumption of all the fuel in the furnace which would result in extinguishment of the fire. In this particular instance the fuel and air feed motors 31 and 32 are operated every time the temperature of combustion falls 60 below the setting of low limit switch 29. Of course, other methods of preventing extinguishment of the fire under low heat requirement conditions could be used if desired.

Assuming, however, that the temperature of 65 combustion falls below the setting of low limit switch 29 indicating that the fire will soon go out if additional fuel and air is not supplied, an energizing circuit for relay coil 33 will be established as follows: hot line 37, wire 38, wire 51, 70 low limit switch 29, wire 52, wire 40, relay coil 33, and wire 41 to ground line 42. Energization of relay coil 33 results in operation of feed motor 31 and fan motor 32 as described heretofore. When the temperature of combustion rises above 75

the setting of low limit switch 29 the circuit to relay coil 33 will be interrupted and the feed motor 31 and fan motor 32 will be stopped.

From the foregoing description it will be evident that this invention provides an efficient automatic method and means for burning solid fuel in which the fuel feed is operated intermittently according to the temperature of combustion and in which the air feed is constantly operated whenever the space to be heated falls below the desired temperature. In combination with these features the invention also provides means for preventing extinguishment of the fire under low heat requirement conditions.

15 Although a specific embodiment of the invention has been herein shown and described it is to be understood that various changes and modifications could be made and we are to be limited only in the purview of the appended 20 claims. While mercury switches have been shown in the combustion thermostat 15 and open contacts have been shown in the room thermostat 10, it is to be understood that either of these thermostats may be provided with any type of 25 contacting mechanism desired and may be modified in construction so long as they perform the necessary functions.

We claim:

1. A control system for an automatic stoker including an air feed and a fuel feed comprising, 30 in combination, a thermostatic device located in the space to be heated, a furnace thermostat directly responsive to the temperature of combustion, means under the control of the thermostatic device for operating the air feed and fuel feed when the temperature of the space to be heated is below that desired, and means under the control of the furnace thermostat for preventing operation of the fuel feed only when the temperature of combustion rises above a predetermined 40 maximum.

2. A control system for an automatic stoker including an air feed and a fuel feed comprising, 45 in combination, a thermostatic device located in the space to be heated, a furnace thermostat directly responsive to the temperature of combustion, means under control of the thermostatic device for operating the air feed and fuel feed when the temperature of the space to be heated is below that desired, means under control of the furnace thermostat for operating the air feed and fuel feed when the temperature of combustion falls below a predetermined minimum, and means under control of the furnace thermostat for preventing operation of the fuel feed only when the temperature of combustion rises above a predetermined maximum.

3. A control system for an automatic stoker including an air feed and fuel feed, comprising, 60 in combination, a thermostatic device responsive to the temperature of the space to be heated, a furnace thermostat directly responsive to the temperature of combustion, means under control of the thermostatic device for operating the fuel feed and air feed when the temperature in the space to be heated falls below a predetermined minimum, and means under the control of the furnace thermostat for stopping and starting the fuel feed as the temperature of combustion rises 65 above and falls below a predetermined maximum temperature during the time the thermostatic device is below the minimum temperature.

4. A control system for an automatic stoker including an electrically operated fuel feed motor 70 and an electrically operated air feed motor com-

prising, in combination, a room thermostat, a combustion thermostat, a source of power, connections for energizing the fuel feed and air feed motors when the temperature to which the room thermostat is subjected falls below a predetermined minimum and other connections controlled by the combustion thermostat for de-energizing the fuel feed motor only when the temperature of combustion rises above a predetermined maximum while the temperature at the room thermostat remains below the desired minimum.

5. A control system comprising, in combination, a room thermostat, a relay controlled thereby, a fuel feed motor, an air feed motor, circuit connections controlled by the relay for energizing the fuel feed motor and the air feed motor, a combustion thermostat and means controlled by the combustion thermostat for preventing operation of the fuel feed motor only when the temperature of combustion rises above a predetermined maximum.

6. A control system for an automatic stoker including an electric motor for controlling fuel feed and a second electric motor for controlling the supply of air comprising, in combination, a room thermostat, a combustion thermostat, a source of power, connections controlled by the room thermostat for operating the fuel feed and air supply motors when the room temperature falls below a predetermined minimum, connections cooperating with the combustion thermostat and fuel feed motor for preventing operation thereof when the temperature of combustion rises above a predetermined maximum while the room temperature remains below the predetermined minimum and other connections cooperating with the combustion thermostat for operating both the fuel feed motor and air supply motor when the temperature of combustion falls below a predetermined minimum while the room temperature is above its predetermined minimum.

7. An automatic control system comprising in combination, a fuel feed motor, an air feed motor, a relay in control of said motors, a room thermostat for energizing the relay to operate the fuel feed and air feed motors when the room temperature falls below a predetermined minimum, a combustion thermostat, a circuit controlled thereby for preventing operation of the fuel feed motor only, when the temperature of combustion rises above a predetermined maximum while the room temperature remains below its predetermined minimum and other circuit connections between the relay and combustion thermostat for energizing the relay when the temperature of combustion falls below a predetermined minimum to operate the fuel feed motor and air supply motor when the room temperature is above its predetermined minimum.

8. An automatic control system comprising, in combination, a room thermostat, a source of power, a relay in circuit with the source of power and room thermostat, a switch operated by the relay, an air feed motor, a fuel feed motor, a circuit for the air feed motor including the source of power, relay operated switch, and air feed motor, a combustion thermostat, a switch operated thereby, and a circuit for the fuel feed motor including the source of power, relay operated switch, combustion thermostat switch and fuel feed motor.

9. A control system comprising in combination, a source of power, a relay, a room thermostat, a combustion controlled low limit switch, parallel circuits for the relay controlled by the room ther-

- mostat and combustion controlled low limit switch, a fuel feed motor, an air feed motor, a switch mechanism operated to closed circuit position when the relay is energized, a circuit for the air feed motor including the source of power and relay controlled switch mechanism, a combustion temperature high limit switch and a circuit for the fuel feed motor including the source of power, the relay controlled switch mechanism and combustion temperature high limit switch.
10. A control system for an automatic stoker including an air feed and a fuel feed comprising, in combination, a thermostatic device located in the space to be heated, a furnace thermostat directly responsive to the temperature of combustion, means under control of the thermostatic device for operating the air feed and fuel feed when the temperature of the space to be heated is below that desired, means under control of the furnace thermostat for interrupting operation of the fuel feed when the temperature of combustion rises above a predetermined maximum, and means for operating the fuel feed sufficiently often to prevent extinguishment of the fire under low heat requirement conditions.
15. A control system for an automatic stoker including an electric motor for controlling fuel feed and a second electric motor for controlling the supply of air comprising, in combination, a room thermostat, a combustion thermostat, a source of power, connections controlled by the room thermostat for operating the fuel feed and air supply motors when the room temperature falls below a predetermined minimum, connections co-operating with the combustion thermostat and fuel feed motor for preventing operation thereof when the temperature of combustion rises above a predetermined maximum while the room temperature remains below the predetermined minimum and means for operating the fuel feed means sufficiently often to prevent extinguishment of the fire under low heat requirement conditions.
20. An automatic control system comprising in combination, a fuel feed motor, an air feed motor, a relay in control of said motors, a room thermostat for energizing the relay to operate the fuel feed and air feed motors when the room temperature falls below a predetermined minimum, a combustion thermostat, a circuit controlled thereby for preventing operation of the fuel feed motor only, when the temperature of combustion rises above a predetermined maximum while the room temperature remains below its predetermined minimum and means for energizing the relay to operate the fuel feed motor and air supply motor sufficiently often to prevent extinguishment of the fire under low heat requirement conditions.
25. A control system for a combustion system including a heater, a fuel feed and an air feed, said control system comprising, means for operating the fuel feed and air feed, a thermostat responsive to a heater condition, and means under the control of said thermostat for only discontinuing operation of the fuel feed and allowing continued operation of the air feed when the temperature to which said thermostat responds rises above a predetermined maximum.
30. A control system for a combustion system including a fuel feed and an air feed, said control system comprising, means for operating the fuel feed and air feed, a thermostat directly responsive to combustion conditions, and means controlled by said thermostat for interrupting operation of the fuel feed and allowing continued operation of the air feed when the temperature of combustion rises above a predetermined maximum, and means for operating the fuel feed sufficiently often to prevent extinguishment of the fire when the combustion system is operating under low heat requirement conditions.
35. A control system for a combustion system including a fuel feed and an air feed, said control system comprising, means for operating the fuel feed and air feed, a thermostat directly responsive to combustion conditions, means controlled by said thermostat for interrupting operation of the fuel feed and allowing continued operation of the air feed when the temperature of combustion rises above a predetermined maximum, and means for operating the fuel feed sufficiently often to prevent extinguishment of the fire when the combustion system is operating under low heat requirement conditions.
40. A system of the class described comprising, in combination, a fuel feed, an air feed, a primary thermostatic control device, means controlled thereby for operating the fuel feed and air feed, a secondary thermostatic control device responsive to a heater condition, and means under the control thereof for interrupting operation of the fuel feed and allowing continued operation of the air feed when the temperature to which said secondary thermostatic control device responds rises above a predetermined maximum.
45. A system of the class described comprising, in combination, a fuel feed, an air feed, a primary thermostatic control device, means controlled thereby for operating the fuel feed and air feed, a secondary thermostatic control device responsive to a heater condition, and means under the control thereof for interrupting operation of the fuel feed and allowing continued operation of the air feed when the temperature to which said second thermostat responds rises above a predetermined maximum and for operating the fuel feed sufficiently often to prevent extinguishment of the fire when operating under low heat requirement conditions.

THOMAS McDONALD.
CLIFFORD J. PAISLEY.
